UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF DELAWARE

SWITCH

Original application filed June 11, 1923, Serial No. 644,679. Divided and this application filed September 20, 1928. Serial No. 393,940.

This invention relates to switches and has for its object to provide switches for controlling lighting and ignition circuits of automobiles and the like and the purpose is to simplify the construction of such switches, making them inexpensive to manufacture as well as strong and durable in use and readily accessible for repairs when necessary.

This application constitutes a division of 10 my application for automobile switch and instrument panels, Serial No. 644,679, filed June 11, 1923.

With the above and other objects in view the invention consists in the switch as herein 15 claimed, its parts and combination of parts, and all equivalents.

Referring to the accompanying drawings, in which like characters of reference indicate the same parts in different views,

20 Fig. 1 is a front view of a lighting switch embodying the invention and Fig. 2 is a rear view thereof;

Fig. 3 is a front view of an ignition switch and Fig. 4 a rear view thereof;

25 Fig. 5 is a central sectional view through one of the switches;

Fig. 6 is a rear view of one of the switches with parts removed to the locking nut;

Fig. 7 is a similar view showing the stop 30 plate in position;

Fig. 8 is an inside view of one of the terminal heads with the contact member and driver in position;

Fig. 9 is a sectional view thereof without 35 the driver;

Fig. 10 is a rear view of the contact member, and

Fig. 11 is a sectional view through the 40 switch handle bushing showing the engagements of the locking plate.

In these drawings, 24 indicates a base casting forming a panel on which is mounted a glass front 27 held in place by a rim or bezel 20.

45 Openings are drilled through the glass to receive flanged tubular bushings 29 for lighting and ignition switch handles 30 and 31 respectively, said bushings also fitting within flanged openings in the base castings 24, 50 where they are held by lock nuts 32 threaded

on them within switch cases 33 formed integral with the base casting. Gaskets of rubber or other suitable material surround the edges of the openings in the glass and fit between the clamping surfaces of the bushing 55 shoulders and the flanges around the openings of the base casting, as shown in Fig. 5, to make a tight fit without undue stress on the glass, and the adjustments of the lock nuts 32 for maintaining the clamping engagement are retained by means of lock plates 34. Each of these lock plates 34, as shown in Fig. 11, is anchored against turning by having notches 35 in its edge to engage one or another of a series of longitudinally extending flanges 36 projecting inwardly from the wall of the switch case 33. At the same time this lock plate anchors the bushing 29 so that it is incapable of turning, the oval shaped opening in said lock plate 60 having an inwardly extending lug 37 to engage in an opening 38 in said bushing, as seen in Figs. 5 and 11. In assembling, the lock plate, because of the elongation of its opening, may be passed over the end of the 65 bushing and then with its lug 37 registering with the opening 38 it may be forced upwardly to effect their engagement, the same movement effecting the engagement of a notch 35 with a flange 36. Then the lock nut 70 is turned on the end of the bushing to effect the desired clamping of the glass front and incidentally serving to clamp the lock plate 75 in place. When this adjustment is effected the lock nut is locked against displacement by bending into one of its peripheral notches 80 39 one or more of the locking fingers 40 which are bent up from the edge of the locking plate and are so spaced that one or another will be convenient for such engagement 85 in any position of the locking nut. In this manner the bushing is prevented from turning by anchoring it to the base casting, the glass is clamped around the bushing to the desired degree to effect a tight connection 90 without undue stress, and the clamping adjustment is rendered permanent by the locking of the clamping nut in its adjusted position. It will be appreciated that this method 95 of adjusting and locking the clamping bush- 100

ing to maintain tight connection with the glass adapts the parts to suit themselves to the thickness of the glass notwithstanding variations in such thickness, so that whether the glass is thin or thick a tight seal may be made that will exclude dust and water where it fits around the bushings and in this way provision is made for passing the switch handles through the glass front.

The construction of the lighting and ignition switches is substantially the same, except for the range of movement being greater with the lighting switch. The range of movement is determined by a stop plate 62 mounted on the stem of the switch handle and having oppositely extending stop lugs to engage the flanges 36 previously mentioned. The end of the stem of the switch handle has a central bore and is slotted with the slot through one wall slightly wider than the slot through the other wall, and openings in the stop plate match with the sectional shape of the slotted bored handle stem, as shown in Fig. 7. A screw 63 in the bore of the stem secures the stop plate to the unslotted portion of the stem, as seen in Fig. 5. This manner of mounting the stop plate on the stem makes it incapable of turning thereon so that when the lugs strike the flanges 36 the handle is incapable of turning further. It will be noted that for modifying the switch for different purposes the range of movement may be increased by removing one or more of the flanges 36.

The contacting portions of the switch are self-contained, that is they constitute an independent assembly readily attachable to the switch housing and comprise an insulating terminal head 64, preferably of one or two sheets of bakelite fabric, having a stud 65 riveted to its center to constitute a pivot post for the contact member. The contact member comprises an insulating plate 66, preferably of vulcanized fiber, rotatably and slidably mounted on the pivot post 65 with radial projections fitting within the correspondingly shaped flanged edges of a metal contact ring 67, whose corresponding radially extending projections are recessed to fit the rivet heads of contact studs 68 arranged in a circle on the terminal head 64 around the pivot post. A U-shaped sheet metal driver 69 is pivotally mounted on the pivot post and bears against the rivet head thereof and one of its legs is wider than the other to correspond with the width of the slots in the switch handle stem and assure proper assembly therewith, for these parts of the driver are contained within the slots of the handle stem when assembled, as shown in Fig. 8, and their ends pass through openings in the insulating plate 66 without contacting with the contact ring. The turning movements of the switch handle are therefore communicated to the driver and through

the driver to the contact member, the position of the driver in the slots of the handle stem being variable to accommodate the varying thickness of the glass front 27. A coiled spring 70 surrounds the pivot post, bearing at one end against the driver 69 and at the other end against the insulating plate 66, thus serving to hold the contact ring firmly in engagement with the rounded heads of the contact studs 68 and causing the recesses in said contact ring in engagement with the heads of the studs to serve as detents for holding the switch in its operative positions. The contact studs 68 serve as rivets for attaching angular binding posts 71 arranged and marked for the various wiring connections to establish the desired switch connections in the various positions of the switch handles. The terminal heads 64 are secured to the ends of the switch housings 33 by means of screws 72, and in addition thereto positioning lugs 73 on the edge of the switch housing enter openings 74 in the terminal heads assuring proper assembly.

What I claim as new and desire to secure by Letters Patent is:

1. In a switch, an insulating terminal head, a pivot post mounted thereon, a U-shaped driver rotatably mounted on the pivot post, an insulating disk rotatably and slidably mounted on the pivot post and having openings to receive the ends of the driver, a coiled spring surrounding the pivot post and bearing on the insulating disk and on the driver, said insulating disk having radially extending arms, a contact ring mounted on the insulating disk by having its edges bent up around said disk and the arms thereof and having contact projections with waved contact surfaces at the radial arms of the insulating disk, contact studs on the terminal head engaged by said contact surfaces of the contact ring, binding posts connected with the contact studs, and means for turning the driver.
2. In a switch, a base, a glass front, a flanged bushing passing through an opening in the glass front and through an opening in the base, a nut threaded on the bushing, means for locking the nut and for preventing the bushing from turning, and a switch on the base having a handle passing through the bushing.
3. In a switch, a base forming a switch housing, a glass front, a shouldered bushing passing through an opening in the glass front and through an opening in the base and entering the switch housing, a flange in the switch housing, a lock plate surrounding the bushing and having a projection entering an opening in the bushing and a notch to fit the flange, a nut threaded on the bushing against the lock plate and provided with notches in its edge, an ear on the lock plate bent into one of the notches of the nut for

locking it, and a switch in the switch housing having a handle passing through the bushing.

4. In a switch, a base, a glass front, a shouldered bushing passing through the glass front and the base, a switch handle fitting in the bushing, a suitably locked adjusting nut on the bushing, a switch housing on the base around the end of the switch handle, a stop plate secured to the switch handle, a projection on the switch housing engaged by the stop plate, and a switch member operated by the switch handle.

5. In a switch, a base, a glass front, a switch handle passing through the glass front and the base, a switch housing formed on the base around the end of the switch handle, a terminal head secured to the end of the switch housing, contact studs mounted on the terminal head, a pivot post mounted on the terminal head, a driver mounted on the pivot post and having slidable driving connection with the end of the switch handle, a spring-pressed insulating member slidably and rotatably mounted on the pivot post and having driving connection with the driver, and a contact member carried by the insulating member and engaging the contact studs.

6. A switch comprising a base, a glass front, a shouldered bushing passing through the glass front and the base, a nut threaded thereon, a switch housing on the base around the end of the switch handle, a flange therein, said end of the switch handle being slotted, a stop plate secured in the slot of the switch handle and engaging the flange of the switch case for limiting the movements of the switch handle, an insulating terminal head secured to the end of the switch housing, contact studs carried thereby, a central pivot post on the terminal head, a driver pivotally mounted on the pivot post and slidably fitting in the slot of the switch handle, a spring-pressed insulating member slidably and rotatably mounted on the pivot post and having a driving engagement with the driver, and contact means carried by the insulating member for engaging the contact studs.

7. In a switch, an insulating terminal head, a pivot post mounted thereon, a driver rotatably mounted on the pivot post, an insulating member rotatably and slidably mounted on the pivot post and splined with the driver, a spring bearing on the insulating member, a contact member mounted on the insulating member, contacts on the terminal head engaged by the contact member and forming an undulating bearing therefor causing relative movement between the contact member and the driver, and means for turning the driver.

8. In a switch, an insulating terminal head, a suitably mounted driver, an insulating member operatively engaged by the driver, pressure means for moving the insu-

lating member on the driver, said insulating member having radially extending arms, a contact member mounted on the insulating member by having its edges bent up around said insulating member and the arms thereof and having contact projections at the radial arms, contacts at the terminal head engaged by the contact projections, and means for turning the driver.

9. In a switch, an insulating terminal head, a pivot post mounted thereon, a switch handle, a driver rotatably mounted on the pivot post and splined with the switch handle, a spring-pressed switch member splined on the driver and insulated therefrom, and contacts on the terminal head engaged by the switch member.

10. In a switch, an insulating terminal head, a headed pivot post mounted thereon, an insulating member rotatably and slidably mounted on the pivot post, a driver rotatably mounted on the pivot post and bearing on the head thereof and splined with the insulating member, a coiled spring surrounding the pivot post between the insulating member and the driver, a contact member mounted on the insulating member, contacts on the terminal head engaged by the contact member causing relative movement between the contact member and the driver, and means for turning the driver.

11. In a switch, an insulating terminal head, a pivot post thereon, a driver rotatably mounted on the pivot post, a spring-pressed insulated switch member rotatably and slidably mounted on the pivot post and splined on the driver, and contacts on the terminal head engaged by the switch member and forming an undulating bearing therefor causing relative movement between the switch member and the driver.

In testimony whereof, I affix my signature.
EDWARD N. JACOBI.
